UNITED STATES PATENT OFFICE

156,588

PLANT CONTAINER

Robert Weber, Los Angeles, Calif.

Application June 6, 1949, Serial No. 3,082

Term of patent 7 years

(Cl. D35—3)

To all whom it may concern:

Be it known that I, Robert Weber, a citizen of the United States, residing in the city and county of Los Angeles and State of California, have invented a new, original, and ornamental Design for a Plant Container, of which the following is a specification, reference being had to the accompanying drawing, forming part thereof.

Fig. 1 is a front perspective view of a plant container, showing my new design.

Fig. 2 is a top plan view.

Fig. 3 is a rear elevation, and

Fig. 4 is a right side elevation.

I claim:

The ornamental design for a plant container, substantially as shown.

ROBERT WEBER.
